UNITED STATES PATENT OFFICE

PAUL LÄUBLI, OF ZOFINGEN, SWITZERLAND, ASSIGNOR TO PAUL RUDOLPH VOIGT, OF CHEMNITZ, GERMANY.

YARN-WINDING APPARATUS.

No. 913,739.

Specification of Letters Patent.

Patented March 2, 1909.

Application filed November 23, 1906. Serial No. 344,764.

To all whom it may concern:

Be it known that I, PAUL LÄUBLI, citizen of the Swiss Republic, residing at Zofingen, Switzerland, have invented certain new and useful Improvements in Yarn-Winding Apparatus, of which the following is a specification.

This invention relates to yarn-winding apparatus.

10 In machines for winding yarn, conical rollers have been arranged adjacent the lower, conical parts of spools or cops in course of formation, thread-guides being suitably reciprocated to lay the thread upon the said 15 conical parts, so that the increasing thickness of the thread-layers gradually-lifts the spools at a rate proportional to the increasing size of the latter.

The present invention also involves the 20 use of a roller against which the lower part of the spool or cop abuts, so that the latter is gradually lifted during the course of the winding process, but the construction and action of the said roller are so modified, that 25 the ordinary thread-guide is dispensed with, the function of guiding the thread being performed by the roller itself. For this purpose a conical part of the latter is provided with an eccentric annular groove which 30 turns upon itself and into which the thread is laid, so that the thread is crosswound in a manner depending on the shape of the groove.

The construction of the apparatus varies 35 in detail according to the particular purpose for which it is designed.

The invention is illustrated in the annexed drawing by means of a device as applied to the winding of weft-cops, but with 40 suitable modifications it can also be applied to variable cross-winding with self-actors, to winding large bobbins, and to other similar purposes.

In the drawing Figure 1 is a side-view, 45 partly in section and Fig. 2 a plan-view of the apparatus. Figs. 3 to 6 are side-views illustrating different stages of the winding process.

The spindle *a* is revolved in the usual manner by means of friction-gear, change-wheels, a strap or cord and pulley, or similar well known mechanism not illustrated. On the spindle is placed the empty spool *b* or tube of 50 pressed paper. For winding coarse cotton or linen yarn it is desirable to use ribbed

spools, but for softer, supple yarns, smooth spools are suitable. The truncated, conical cup or roller *c*, which constitutes the essential feature of the invention, may be constructed of wood, glass, cast-iron or other suitable material, and is provided with an elongated hub-part *d*, by means of which it is loosely mounted on an axle *e*, the latter being fixed to a holder *f* rotatable and adjustable on an axle *g*. The geometrical axis 60 of the axle *g* is tangential to the spindle *a*, so that by adjusting the angle of inclination of the axle *e* the cup or roller *c* can be adjusted to coact with spools of all degrees of conicity.

In the outer, conical surface of the roller *c* 70 is formed the eccentric guide-groove *i* already referred to, the said groove being in the example illustrated substantially heart-shaped, as shown in Figs. 3 to 6.

The action of the apparatus described will 75 be readily understood by reference to Figs. 3 to 6, showing successive positions of the thread *k*. The position of contact between the cup *c* and the spool remains unchanged during the winding operation, but the thread 80 *k* engaged by the guide-groove *i* is during this operation displaced in accordance with the changing position of the latter.

To prevent access of the lubricating oil to the thread, the hub-part *d* has no orifice at 85 the end adjacent the cup, as is shown in Fig. 1; the outer surface of the cup is, therefore, continuous. The facility with which the cup is revolved is such that slight differences in the dimensions of the spools used are immaterial, such differences being neutralized after a few revolutions of the cup. When 90 the spindle *a* is started rotation is immediately imparted to the cup *c*, and the thread *k*, is reciprocated by reason of its engagement with the groove *i*, and is therefore cross-wound on the coil *m*. The friction to which the thread is subjected when passing on to the spool is negligible, the groove *i* being comparatively wide, and the thread is 100 wound in curved lines, without making angles such as occur with some systems of winding. The friction between the revolving cup *c* and the cop or spool *m* is so slight 105 that the most sensitive and delicate yarn can be wound without injury, whereas with ordinary cones, such as have hitherto been used, breakages are frequent. Even with very slight yarn-tension and yarn of poor quality, the winding is very firm, and this is 110

of course of great advantage in cops and bobbins used for weaving purposes. If the cup *c* has a few millimeters play, cops of different thicknesses can be wound, but for simplicity 5 and cheapness it is preferable that the cup should be stationary and merely rotatable about its axis, as shown in the drawing, and even under these conditions differences of from 2 to 3 millimeters in the cop-diameter 10 are possible. If the difference is greater than say 3 millimeters, all that is required is to use a thicker or thinner spool. It has been found that there is no risk whatever of the thread slipping out of the groove, provided 15 that the cup is adjusted with moderate accuracy.

The simplicity of the invention allows of applying it, at small cost, to existing winding-machines, the out-put of which is doubled or trebled by this means. A very 20 considerable reduction of working expenses results from the fact that only the spindle need be driven.

Having now fully described my invention 25 I declare that what I claim is:—

1. In a yarn-winding apparatus the combination of a rotated spool, a revoluble roller driven by said spool and arranged adjacent thereto and an eccentric groove provided in 30 the outer circumference of said roller adapted to engage a thread and pass it on to said spool the rotative axis of the roller being angularly disposed with respect to that of the spool.

2. In a yarn-winding apparatus the combination of a rotated shaft, a spool fixed thereto, a roller driven by said spool and adapted to contact said spool, a groove in said roller adapted to engage a thread and pass it on 40 said spool the rotative axis of the roller being angularly disposed with respect to that of the spool.

3. In a yarn-winding apparatus the combination of a rotated shaft, a spool fixed thereto, a roller driven by said spool and arranged adjacent thereto and means for passing a 45

thread engaging said roller to said spool the rotative axis of the roller being angularly disposed with respect to that of the spool.

4. In a yarn-winding apparatus the combination of a rotated spool, a truncated conical roller driven by said spool and adapted to abut said spool and cross-wind a thread engaging its outer circumference on said spool the rotative axis of the roller being angularly 50 disposed with respect to that of the spool.

5. In a yarn-winding apparatus the combination of a rotated spool, a truncated conical roller driven by said spool and adapted to contact said spool, an eccentric groove returning upon itself provided in the outer circumference of said roller adapted to engage a thread and wind it on said spool the rotative axis of the roller being angularly disposed with respect to that of the spool. 60

6. In a yarn-winding apparatus the combination of a rotated spool, a truncated conical roller driven by said spool and adapted to contact said spool, a heart shaped groove provided in the outer circumference of said roller 70 adapted to engage a thread and pass it up and down said spool the rotative axis of the roller being angularly disposed with respect to that of the spool.

7. In a yarn-winding apparatus the combination of a driven spindle, a spool fixed thereto, an axle, a truncated conical cup arranged loosely thereon adapted to contact and be driven by said spool by its outer circumference, the rotative axis of said cup being angularly disposed with respect to that of the spool, a cam groove provided in said outer circumference of said cup adapted to engage a thread and pass the latter to said spool thereby reciprocating it thereon. 80

In testimony whereof I affix my signature in presence of two witnesses.

PAUL LÄUBLI.
